UNITED STATES PATENT OFFICE

KIICHIRO TOYODA, OF TOKYO, JAPAN

SAFETY DEVICE FOR SHUTTLE-CHANGING APPARATUS FOR USE IN AUTOMATIC LOOMS

Application filed December 24, 1929, Serial No. 416,273, and in Japan September, 1929.

My invention relates to automatic looms and has for its particular object to provide a safety device adapted for use in the shuttle changing mechanism in such looms, in which the shuttle is replenished by another shuttle actuated by a weft fork and/or feeling motion, without the stopping of or reduction in the speed of the operation of the loom.

Hereinafter, such an automatic loom will be referred to as a non-stop shuttle changing automatic loom to thereby distinguish from an automatic loom in which the shuttle replenishing motion is accomplished, after the loom has first been stopped, or its speed temporarily decreased from its normal speed.

In non-stop shuttle changing automatic looms, it may occur for unforeseen reasons, that a shuttle or shuttles and/or parts of the shuttle changing mechanism are damaged whereby the proper action of the mechanism is interfered with.

The chief object of the present invention is to provide means for absolutely preventing such an occurrence thereby protecting the shuttles and every part of the shuttle changing mechanism against possible damage.

While in the appended drawing, I have by way of example, illustrated an embodiment of the safety device in accordance with this invention as applied to a non-stop shuttle changing automatic loom, the invention is, of course, not confined to this particular loom. In the drawing, Fig. 1 is a side view of the safety device attached to the shuttle changing mechanism, in inoperative position, parts being shown in section, while Fig. 2 is a similar view as Fig. 1 but showing the device in operation.

In the drawing, 1 is the slay sword, 2 a part of the frame of the loom, 3 the front plate of the shuttle box, 4 the guide plate, 5 the back plate and 6 the rocker arm connecting the front plate 3 and back plate 5. 7 is the receiving rod to which the lower arm of a two-arm lever 8 is pivotally connected. 8 is pivoted to the frame by means of a central pivot. The shuttle magazine 11 is suspended on the frame by means of a pivot pin 11' about which the magazine 11 may be freely rocked, tho it is normally held in a perpendicular

position by its weight and a stop attached to frame 2. 13 is a protecting lid for the shuttle ejecting rods 10 and their guides, which lid is hinged to the magazine 11 by the pin 13a. At 14 is shown a spring whereby a pin 8' of semi-circular cross-section on the end of lever 8 is pressed into a similarly shaped recess provided at the end of a rod 9, so that the latter and lever 8 are pivotally connected by pin 8', while spring 14 maintains the pin 8' in position in the semi-circular recess of rod 9.

An angular finger 15 is pivoted at the bottom corner of magazine 11 by a pivot pin 16 so as to have a free swinging movement. From the horizontal part of the finger is suspended a rod 17. To the lower end of said rod 17 a catch C is pivoted. As shown in Fig. 2, a projecting arm 18 is secured to the back plate 5 (or front plate as the case may be) of the shuttle box. 19 is an abutment screw threaded into a rod 20 pivoted to the loom frame by means of pivot pin 21 and a bracket. To the lower end of rod 20 is pivotally connected a rod 22 which latter is operatively connected with a stop motion of the loom.

The safety device, according to this invention, fully protects all parts of the shuttle changing apparatus, shuttle box, and the shuttles insuring perfect operation of the loom in the following cases:

1. When the magazine 11 becomes empty, or when the lowest shuttle is wrongly placed, or in case a wrong shuttle as to size and shape is placed in the magazine by mistake and when it comes to the lowest position, the loom is automatically stopped by means of the finger 15, the upper part of which under normal circumstances is maintained at a certain position by a properly placed shuttle of the correct size so that through the rod 17 catch C is held in a position to clear a hook (D) secured to the slay (1), which moves back and forth all the time. But in case of no shuttle being left in the magazine, or in case of too small a shuttle being present, to keep the upright part of finger 15 held out in the proper position, the finger fulcrumed at 16 will be moved into the space in the magazine box by the weight of rod 17 and catch 18.

C, permitting the latter to move into the path of the hook D on the slay, the motion of which is transmitted through rods and links in the usual way to the stop mechanism with the result that the loom is instantaneously stopped.

2. When the shuttle change motion takes place, but for some reason something other than the shuttle which is to be replaced, 10 should come in the way of the motion (the picker, for instance) preventing the shuttle from being ejected from the magazine into the shuttle box, such force will soon overcome the pressure of the spring 14 so that the pin 15 8' of lever 8 will become disengaged from rod 9, which thereby is released from the movement of lever 8. The further forward movement of rod 9, therefore, is stopped by the resistance while lever 8 alone moves forward as usual. In this way damage to any 20 part of the magazine or to the shuttles or even to the material which came in the way is effectively prevented. Furthermore, as lever 8 makes its return stroke, rod 9 is thereby pushed back beyond its original position because this time the end of the rod 9 is pushed by the end of lever 8, instead of by the pivot pin 8'. By this additional movement of rod 9 the lid 13 is pushed away from 30 its normal position together with the magazine box 11, which rocks about its pivot 11'.

This motion results in the disengagement of finger 15 from the rod 17, which in dropping actuates the stop motion in same manner as before.

3. After the completion of the shuttle change motion, but in case of any part or parts of the shuttle box not properly returning to their original position, the projection 40 18 attached to the back plate 5 of the shuttle box (or front plate as case may be) strikes the abutment screw 19 as slay (1) moves backwards causing rod 20 fulcrumed at 21 to swing back, thereby pulling rod 22 45 in the direction of the arrow shown in Fig. 2. Rod 22 being connected to the stop motion, the loom is instantaneously stopped.

I claim:

1. In automatic looms, in combination with 50 the shuttle-box, the shuttle changing mechanism and the stop mechanism, a movable shuttle magazine, a shuttle ejecting member, a guide therefor connected to the said shuttle magazine, a lever normally operatively connected with said shuttle ejecting member but adapted to be disconnected therefrom by abnormal resistance to said shuttle ejecting member and on its return stroke to engage with, and push back, said shuttle ejecting member and said guide member to move 55 said shuttle magazine, and a member on said shuttle magazine operatively connected to said stop mechanism and adapted to actuate said stop mechanism upon the movement of 60 said shuttle magazine.

2. The combination as specified in claim 1, wherein said member on the shuttle magazine comprises an angular finger pivoted to said shuttle magazine and adapted to be rocked on said shuttle magazine becoming empty or on the lowest shuttle being wrongly placed, so as to actuate said stop mechanism.

3. The combination as specified in claim 1, wherein said lever is provided with a pin of 75 semi-circular cross section pressed by a spring into a similarly shaped recess of said shuttle ejecting member thereby pivotally and detachably connecting said lever and said shuttle ejecting member.

In testimony whereof I affix my signature.
